(57) CLAIM

The ornamental design for a carpeted sandal, as shown and described.

DESCRIPTION

FIG. 1 is a top view of the carpeted sandal, showing my new design;

FIG. 2 is a bottom view.

FIG. 3 is a left side view.

FIG. 4 is a right side view.

FIG. 5 is a front view; and,

FIG. 6 is a rear view.

The broken line showing is included for the purpose of illustrating and forms no part of the claimed design.
